UNITED STATES PATENT OFFICE.

WALTER J. ROOTS, OF PORTLAND, OREGON.

AUTOMOBILE HEATING APPARATUS.

1,162,105.

Specification of Letters Patent. Patented Nov. 30, 1915.

Application filed December 11, 1914. Serial No. 878,752.

To all whom it may concern:

Be it known that I, WALTER J. Roots, a citizen of the United States, and a resident of the city of Portland, State of Oregon, have invented a new and useful Improvement 5 in Automobile Heating Apparatus, of which the following is a specification.

My invention relates to an improvement in means installed in engine-driven vehicles, 10 for utilizing the exhaust from the engine as a heating medium.

The object of my invention is to arrange the heating means in the form of a register located in the vehicle body, and to adapt the 15 register to be opened and closed at will, for admitting heat into the vehicle body or excluding the same, as desired.

To this end my invention comprises a heating drum located in a heating opening there- 20 for provided in the vehicle body, the drum being connected in the exhaust conduit of the engine. Above the drum is a grating, and on the drum is a fender circumferentially movable about the drum and partially 25 inclosing the same. When in one position the surface of the drum exposed in the heating opening of the vehicle body is uncovered, so that heat may be radiated from the heating drum, while in the other adjustment 30 of the fender the drum is covered so as to prevent any radiation of heat therefrom into the vehicle body.

The details of construction and operation 35 of my device are hereinafter fully explained.

In the accompanying drawings, Figure 1 is a side elevation of an automobile, showing my device used in connection therewith. This view shows the exhaust pipe of the engine and the location of the heating drum, 40 which in this case is the muffler, relative to the floor of the car. The door of the tonneau of the machine is shown open and it will be seen that my device is arranged so as to replace the ordinary footrail. Fig. 2 is a 45 larger sized view taken approximately on the line 2—2 of Fig. 1. Fig. 3 is a trans- 50 verse vertical section taken on the line 3—3 of Fig. 2. Fig. 4 is an elevation showing the revoluble sleeve which incloses the muf- 55 fler, and which is adapted to direct the heat in the direction desired, and Figs. 5 and 6 are sectional views taken approximately on the line 5—5 of Fig. 4, showing the extreme 60 positions to which the sleeve may be rotated.

55 a, represents an automobile of standard construction in which my device is installed. b, is the exhaust pipe leading from the en-

gine, c is the muffler and d is the pipe through which the gases are expelled to the atmosphere. The muffler, c, is of standard 60 construction and comprises three rigid concentric cylinders, e, f, and g, fixed between the heads h and i. The exhaust pipe, b, connects directly with the cylinder, e, and the pipe, d, connects directly with the cylinder g. The cylinders e and f are provided with holes e' and f' respectively, through which the gases pass in their transit from the pipe b to the pipe d. Concentric with, and inclosing the cylinder g, is a revoluble 70 cylinder, j. Said cylinder, j, is provided with a cut-away portion, k, and slots m and n, these latter permitting the cylinder to be rotated a maximum degree relative to the fixed pipe, d. Said cylinder is provided 75 with a lining of asbestos, as indicated by o. Furthermore, the cylinder is provided with a peripheral flange p, and an extension spring q, encircles said sleeve, being confined between the sleeve q and the cylinder head i. 80 The expansion of this spring tends to act as a retarding device to hold the cylinder in any position to which it has been rotated.

On one end of the device is a projection r, adapted to be operated by the foot of the 85 occupant of the car so as to thereby rotate the cylinder. The heads h and i are provided with brackets h' and i' which are adapted to be bolted to the floor, a' of the car in connection with which my device is 90 installed. It will be noticed that the muffler extends partially above the floor of the car. A register t, is placed over the muffler, said register being provided with a slot, u, in 95 which the projection r is adapted to move.

The operation of my device is as follows: When the atmosphere of the car is suffi- 100 ciently warm, the cylinder is rotated so as to bring it in the position shown in Figs. 2 to 5 inclusive. The radiated heat from the muffler is then directed downward beneath the floor of the car. When, however, it is desired to utilize this heat, the cylinder is rotated to the position shown in Fig. 6. The radiated heat from the muffler is then 105 conveyed directly to the body of the car and serves as a heating medium. The cylinder may be rotated any distance as desired, for partially or entirely opening or entirely closing the register, and thereby regulating 110 the heating of the body of the car.

I claim:

1. In an engine driven vehicle, a body provided with an opening, a drum located

- in such opening and exposed partly within and partly without the vehicle, said drum being connected in the exhaust conduit of the engine, a fender movable circumferentially about the drum and partially inclosing the same, said fender adapted to cover that portion of the drum without the vehicle when moved to expose the drum within the vehicle.
10. 2. In an engine driven vehicle, a body provided with an opening, a drum located in such opening and exposed partly within and partly without the vehicle, said drum being connected in the exhaust conduit of the engine, a fender movable circumferentially about the drum and partially inclosing the same, said fender adapted to cover that portion of the drum without the vehicle when moved to expose the drum within the vehicle, and means for restraining the circumferential movement of the fender.
15. 3. In an engine driven vehicle, a body provided with an opening, a drum located in such opening and exposed partly within and partly without the vehicle, said drum being connected in the exhaust conduit of the engine, a fender movable circumferentially about the drum and partially inclosing the same, said fender adapted to cover that portion of the drum without the vehicle when moved to expose the drum within the vehicle, said fender consisting of an outer shell and an inner insulating lining, and means for restraining the circumferential movement of the fender.
20. 4. In an engine driven vehicle, a body provided with an opening, a drum located in such opening and exposed partly within and partly without the vehicle, said drum being connected in the exhaust conduit of the engine, a grating over the drum, a fender movable circumferentially about the drum and partially inclosing the same, said fender adapted to cover that portion of the drum without the vehicle when moved to expose the drum within the vehicle, a slot in the grating and a pin projecting from the fender movable in said slot for positioning the fender over the drum.
25. 5. In an engine driven-vehicle, a body provided with an opening, bearing-heads secured in the ends of such opening, a heating drum located between said heads and exposed partly within and partly without the vehicle, said drum connected in the exhaust conduit of the engine, and a cylindrical fender movable circumferentially about said drum, said fender adapted to cover that portion of the drum without the vehicle when moved to expose the drum within the vehicle.
30. 6. In an engine driven-vehicle, a body provided with an opening, bearing-heads secured in the ends of such opening, such heads having peripheral flanges on their inner sides, a heating drum located between said heads, said drum connected in the exhaust conduit of the engine, a cylindrical fender movable circumferentially about said drum and within said flanges of the heads, said fender adapted to cover that portion of the drum without the vehicle when moved to expose the drum within the vehicle; such fender made of an outer shell provided with an interior insulation.
35. 7. In an engine driven-vehicle, a body provided with an opening, bearing-heads secured in the ends of such opening, such heads having peripheral flanges on their inner sides, a heating drum located between said heads, said drum connected in the exhaust conduit of the engine, a cylindrical fender movable circumferentially about said drum and within said flanges of the heads, such fender made of an outer shell provided with an interior insulation, a peripheral flange on the fender located adjacent the head at the outlet end of the drum, and a coil spring between said flange of the fender and said adjacent head.
40. 8. In an engine driven-vehicle, a body provided with an opening, bearing-heads secured in the ends of such opening, such heads having peripheral flanges on their inner sides, a heating drum located between said heads, said drum connected in the exhaust conduit of the engine, a cylindrical fender movable circumferentially about said drum and within said flanges of the heads, such fender made of an outer shell provided with an interior insulation, a peripheral flange on the fender located adjacent the head at the outlet end of the drum, and a coil spring between said flange of the fender and said adjacent head.
45. 9. In an engine driven-vehicle, a body provided with an opening, bearing-heads secured in the ends of such opening, such heads having peripheral flanges on their inner sides, a heating drum located between said heads, said drum connected in the exhaust conduit of the engine, a cylindrical fender movable circumferentially about said drum and within said flanges of the heads, such fender made of an outer shell provided with an interior insulation, a peripheral flange on the fender located adjacent the head at the outlet end of the drum, a coil spring between said flange of the fender and said adjacent head, a grating over the drum, a slot in the grating and a pin projecting in said slot from the fender for positioning the latter.
50. 10. In an engine driven-vehicle, a body provided with an opening, bearing-heads secured in the ends of such opening, a heating drum located between said heads and exposed partly within and partly without the vehicle, said drum connected in the exhaust conduit of the engine, and a cylindrical fender movable circumferentially about said drum, said fender adapted to cover that portion of the drum without the vehicle when moved to expose the drum within the vehicle.
55. 11. In an engine driven-vehicle, a body provided with an opening, bearing-heads secured in the ends of such opening, such heads having peripheral flanges on their inner sides, a heating drum located between said heads, said drum connected in the exhaust conduit of the engine, a cylindrical fender movable circumferentially about said drum and within said flanges of the heads, such fender made of an outer shell provided with an interior insulation, a peripheral flange on the fender located adjacent the head at the outlet end of the drum, a coil spring between said flange of the fender and said adjacent head, a grating over the drum, a slot in the grating and a pin projecting in said slot from the fender for positioning the latter.
60. 12. In an engine driven-vehicle, a body provided with an opening, bearing-heads secured in the ends of such opening, such heads having peripheral flanges on their inner sides, a heating drum located between said heads, said drum connected in the exhaust conduit of the engine, a cylindrical fender movable circumferentially about said drum and within said flanges of the heads, such fender made of an outer shell provided with an interior insulation, a peripheral flange on the fender located adjacent the head at the outlet end of the drum, a coil spring between said flange of the fender and said adjacent head, a grating over the drum, a slot in the grating and a pin projecting in said slot from the fender for positioning the latter.
